UNITED STATES PATENT OFFICE.

GEORGE MARTIN BRILL, OF PHILADELPHIA, PENNSYLVANIA.

DESIGN FOR A SEAT END FOR CAR-SEATS.

SPECIFICATION forming part of Design No. 23,803, dated November 13, 1894.

Application filed October 9, 1894. Serial No. 525,432. Term of patent 14 years.

To all whom it may concern:

Be it known that I, GEORGE MARTIN BRILL, a citizen of the United States, residing at Philadelphia, in the county of Philadelphia and State of Pennsylvania, have invented and produced a new and original Design for a Seat End for Car-Seats, of which the following is a specification.

My invention relates to the design for a seat end for cars, and consists in the shape or configuration of the same.

Reference is had to the accompanying drawings forming part of this specification, in which—

15 Figure 1 is a plan view; Fig. 2, a side elevation; Fig. 3, a side elevation on the side opposite Fig. 2; Fig. 4, a plan view of the under side reversing Fig. 1, and Fig. 5, a sectional elevation on the line xx , Fig. 4, looking in the 20 direction of the arrow.

The seat end in plan is substantially rectangular and in side elevation disposed generally on that figure but altered by curves into a dumb-bell shape. It comprises two 25 walls 1, 2, the wall 1 being vertical, and 2 horizontal, the side and bottom opposing both walls being open as shown in Figs. 3 and 4. The wall or top 2 is concave, and has curved or segmental and enlarged ends 3, which extend but a short distance in return, as shown 30 in Figs. 3 and 4. Midway between the ends 3 the wall or top 2 is provided with a rectangular aperture 4. The vertical wall 1 takes the shape in side elevation of that of the wall 35 or top 2 where the two merge. The lower portion of the wall 1 is straight, as at 5, for a dis-

tance less than its entire length, and at the extremities of the straight sections 5 are two outwardly extending lugs or projections 6, which also depend below the bottom of the 40 wall 1, and centrally between the projections 6 the said wall is curved upwardly, as at 7. Above the curved portion 7 the wall 1 is provided with circular apertures 8, and at the ends with larger apertures 9. The projections 6 are also provided with apertures 10.

From the projections 6 rearwardly and upwardly to the top wall 2 extend inclined ribs or webs 11; and within the ends 3, and extending vertically and midway transversely 50 are ribs or webs 12; and extending rearwardly from the ribs 12 from near the top thereof, and at right angles thereto are wings 13, which are provided with apertures 14, as are also the ribs 12 provided with apertures 15. 55

It will be noticed by reference to Figs. 2 and 3 that the ribs and wings 12 and 13 extend out beyond the terminations of the curved ends 3, and that the apertures 9 in the wall 1 align with the apertures 15 in the 60 rib 12.

Having described my invention, I claim—

The design for a seat end for car seats, substantially as herein shown and described.

Signed at Philadelphia, in the county of 65 Philadelphia and State of Pennsylvania, this 31st day of August, 1894.

GEORGE MARTIN BRILL.
